HAMPER LID FASTENING MECHANISM

Harold Matthews, James Henry Warntjes, Edward Arthurs, and William Carl Wilkinson, Calipatria, Calif., assignors of one-fourth to San Diego Fruit and Produce Company, San Diego, Calif., a corporation of California

Application September 19, 1934, Serial No. 744,688

11 Claims. (Cl. 140—93)

Our invention relates to hamper lid fastening mechanisms and the objects of our invention are:

First, to provide a mechanism of this class which is particularly arranged to act upon light wooden hampers, such as used in packing green peas, wherein the lids are previously provided with securing staples disposed so as to be readily forced into the hampers;

Second, to provide a mechanism of this class which is an improvement of our Basket and hamper fastening machine, Patent Number 1,944,254, issued January 23, 1934;

Third, to provide a mechanism of this class wherein the hamper lid and hamper are held in fixed relation to the mechanism and to each other during the stapling operation; there being incorporated a novel staple engaging arrangement;

Fourth, to provide a mechanism of this class wherein the lidding operation may begin immediately upon positioning the hamper and lid relative to each other and is accomplished with a single rapid movement;

Fifth, to provide a mechanism of this class which incorporates a novelly arranged ejecting means operable automatically immediately upon action of the staple engaging arrangement whereby the lidding and ejecting operation is accomplished with particular rapidity;

Sixth, to provide a mechanism of this class while rapid in its action adequately supports the relatively frail hamper and lid to prevent any crushing thereof or damage to the contents; and

Seventh, to provide on the whole a novelly constructed hamper lid fastening mechanism which is simple and compact of construction, proportional to its functions, durable, efficient in its action, and which will not readily deteriorate or get out of order.

With the above and other objects in view as may appear hereinafter, reference is made to the accompanying drawings wherein similar characters of reference denote similar parts and portions.

In the drawings: Figure 1 is a partially side elevational, partially sectional view of our hamper lid fastening mechanism with its support and operating rod shown fragmentarily and the various parts in the positions assumed upon completing the stapling operation; Figure 2 is a sectional view thereof through 2—2 of Figure 3 with parts and portions in elevation and arranged in the positions assumed before the stapling operation; Figure 3 is a partially plan, partially sectional view thereof taken through 3—3 of Figure 2; Figure 4 is a plan view of the ejector operating

means; Figure 5 is an enlarged fragmentary sectional view of a hamper holding finger taken through 5—5 of Figure 3; and Figure 6 is an enlarged fragmentary sectional view of a hamper guide taken through 6—6 of Figure 3.

The mechanism here illustrated is mounted in cooperative relation with a universally adjustable hamper supporting means such as that illustrated in the aforementioned patent issued to ourselves. From a suitable base, not shown, extends a post 1 at the upper end of which is a forwardly directed arm 1a terminating in a downwardly directed tubular stem 1b. The lower end of the stem 1b carries a flange 1c.

A plate 2 is rigidly suspended from the flange 1c in spaced relation therewith by means of lugs 2a and suitable bolts. The plate 2 carries a centered boss 2b which has a bore therethrough. The boss 2b receives a shaft 3 which extends upwardly through the stem 1b and through a sleeve 1d at the upper end thereof. The lower end of the shaft 3 carries an ejector disk 4 which sets into a recess formed in the under side of the plate 2 so as to be flush therewith. The under side of the plate 2 is dished upwardly to form a concavity 25 which allows the hamper lid, designated L, to assume a convex form. The stem is normally held in its upper position with the disk 4 as its recess by means of a spring 5 and a collar 6.

The periphery of the plate 2 is provided with a plurality of depending, equally spaced brackets 7. Each bracket carries a guide bar 8 which is supported therefrom by laterally extending pins 9 which extend through the bracket and are provided with heads for limiting radially inward movement of the guide bar. The guide bars are turned outwardly at their lower extremities to engage the upper edge of a hamper H and guide the same into centered relation with the plate 2 and the lid L carried thereby.

The centered boss 2b of the plate 2 journals a flat disk 11 which lies contiguous to the upper side of the plate 2. The disk 11 is connected by a series of links 12 to a plurality of radially shiftable finger members 13, the finger members being mounted in radially extending guides or sleeves 2c disposed around the margin of the plate 2. The finger members are provided with depending portions 13a which overhang the periphery of the plate and are slightly inturned at their extremities as shown best in Figure 5 to hold the lid L. The depending portions 13a are relatively flat and pointed. These portions fit within the upper end of the hamper H as it is guided into position and reinforce the hamper during the

stapling operation as will be brought out hereinafter.

One of the fingers 13 is provided with a handle 13b which is adapted to be engaged by the operator to move the several fingers radially outwardly, simultaneously, this movement being accomplished by reason of the links 12 and disk 11. Return movement is accomplished by a spring 14 attached to one of the links 12 and anchored to 10 the plate 2.

The several fingers 13 are preferably grouped in pairs, each pair being disposed between a pair of brackets 7. Between the members of each pair of fingers 13 there is hinged to the plate 2 a stapling lever 15. Each stapling lever includes a broad stapling arm 15a which is shiftable from an outwardly directed relationship with the plate to a slightly inwardly inclined and depending position paralleling the sides of the hamper H as shown in Figures 2 and 1 respectively. A second arm 15b extends upwardly and is connected by an adjustable connecting rod 16 to a collar 17 which is slidably mounted on the stem 1b.

Above the hinged connections with the rods 16 the collar is provided with trunnions 17a which journal a yoke 18a provided at an end of an operating lever 18. The lever 18 extends toward and around the post 1 and is fulcrumed therefrom by means of a compensating link 19 and bracket bearing 20. Beyond the fulcrum of the lever 18 is a short arm 18b to the end of which is attached a spring 21 shown fragmentarily. At a point forwardly of the post 1, that is, between the post 1 and stem 1b the lever 18 is connected to an operating rod 22, shown fragmentarily. The operating rod is connected to any suitable control means, not shown.

The laterally extending arm 1a supports by means of a bracket bearing 23 a rocker arm 24. One end of the rocker arm 24 is hinged to a rod 25 which extends downwardly through the arm 1a and is slidably and pivotably secured by any suitable means to the lever 18. The rod 25 is provided with a stop 25a at its extended end to limit its sliding connection with the lever 18. A spring 26 surrounds the rod 25 and extends between its upper end and the lever 18.

The rocker arm is preferably double; that is, it comprises two parallel disposed portions. 50 These extend forwardly of the fulcrum point of the rocker arm and embrace the upper end of the shaft 3. The portions of the rocker arm receive therebetween a slide member 27 which is guided in longitudinally shiftable relation with the rocker arm. The slide member is provided with an aperture 27a adapted to receive the end of the shaft 3. The slide member is also provided with a slot 27b which fits over a wedge shaped cam member 28 extending upwardly from the arm 1b. The operating side of the cam faces the shaft 3 and is so arranged that upward movement of this end of the rocker arm permits rearward shifting of the slide member while downward movement causes forward shifting of the slide member. A spring 29 holds the slide member in engagement with the cam 28.

Our mechanism is adapted to act upon the conventional green pea hamper and its lid or any other light wooden hamper. However, the lid is first provided with staples S each of which has been previously secured therein by one end leaving a protruding portion S1 with a depending prong S2, the prong being inturned slightly. One stapling lever is provided for each staple.

Our mechanism is operated as follows:

A lid L equipped with the above described staples S is positioned adjacent the plate 2 and held there by the fingers 13. Thereupon the mechanism is lowered as a unit or a hamper is raised until the upper end is guided by the guide bars 8 into juxtaposition with the lid. The operating rod 22 is then pulled downwardly causing the collar 17 to descend and rotate the stapling arms 15a of the stapling levers inwardly to engage the several staples S and force the prongs S2 into the hamper. The dished form of the plate 2 allows the lid to bow upwardly from the pressure of the contents of the hamper. It should be noted that the prongs 13a of the fingers 13 fit between the lid and inside of the hamper 15 to hold the hamper as the prongs are pressed therein.

During downward movement of the collar 17, the end of the rocker arm 24 bearing the slide 27 is raised until the slide member clears the shaft 3 whereupon the spring 29 pulls the aperture 27a out of registry with the stem. Upon subsequent upward movement of the collar 17, and shifting of the stapling levers clear of the hamper, the spring 26 causes the slide member to 25 bear down upon the shaft 3 and cause the disk 4 to force the hamper from the mechanism. Whereupon, the aperture 27a again registers with the shaft and the disk 4 again returns to its retracted position. It should be noted that the 30 spring 26 is made sufficiently strong to overcome the action of the spring 5 and friction between the hamper and guide bars 8.

We claim:

1. In a mechanism for fastening lids on 35 hampers wherein the lids have been previously equipped with securing devices, a lid backing plate, lid holding means arranged around the periphery of said plate, a hamper guiding means for directing a hamper into juxtaposition with the lid retained by said holding means, elements extending from the backing plate and engageable with said securing devices, operating means for said elements, an ejector including an operating end mounted in said backing plate, and an 45 instrumentality operatively connecting the ejector with said operating means.

2. A lid fastening mechanism operable on 50 hamper lids wherein the lids have been previously equipped with securing devices and the lid fastening mechanism includes a lid backing plate and lid holding means arranged therearound, the combination with said backing plate of an ejecting plunger, and link and lever means operatively connecting said plunger with said lid 55 fastening mechanism.

3. A lid fastening mechanism operable on 60 hamper lids wherein the lids have been previously equipped with securing devices and the lid fastening mechanism includes a lid backing plate and lid holding means arranged therearound, the combination with said backing plate of an ejecting plunger, yieldable means normally holding said plunger in a retracted position, operating means for said plunger, an instrumentality for 65 disengaging said operating means from said plunger, a device for resetting said means into engagement with said plunger, and connecting means for operatively associating said plunger with said lid fastening mechanism to eject upon 70 completion of the fastening operation.

4. In a mechanism for fastening lids on 75 hampers wherein the lids have been previously equipped with securing devices, a lid holding means, a hamper guiding means for directing a

hamper into juxtaposition with a lid retained in said lid holding means, elements arranged in proximity with said lid holding means to engage said securing devices, means for simultaneously operating said elements, an ejecting plunger engageable with the lid to force the same from said lid holding means, yieldable means normally holding said plunger in a retracted position, operating means for said plunger, an instrumentality for disengaging said operating means from said plunger, a device for resetting said means into engagement with said plunger, and connecting means for operatively associating said plunger with said element operating means to eject the lid upon action of said elements.

5. In a mechanism for fastening lids on hampers wherein the lids have been previously equipped with securing devices, a lid backing plate, lid holding means arranged around the periphery of said plate, a hamper guiding means for directing a hamper into juxtaposition with the lid retained by said holding means, elements extending from the backing plate and engageable with said securing devices, operating means for said elements, an ejecting plunger mounted in said backing plate, yieldable means normally holding said plunger in a retracted position, operating means for said plunger, an instrumentality for disengaging said operating means from said plunger, a device for resetting said means into engagement with said plunger, and connecting means for operatively associating said plunger with said element operating means to eject the lid upon action of said elements.

35. In a mechanism for fastening lids on hampers wherein the lids have been previously equipped with securing devices, a frame, a lid backing member suspended therefrom, an ejecting plunger including a head centered in said backing member and a shaft guided in said frame, yieldable means normally holding said plunger in a retracted position, operating means for said plunger, an instrumentality for disengaging said operating means from said plunger, and a device for resetting said means into engagement with said plunger.

40. In a mechanism for fastening lids on hampers wherein the lids have been previously equipped with securing devices, a frame, a lid backing member suspended therefrom, an ejecting plunger including a head centered in said backing member and a shaft guided in said frame, yieldable means normally holding said plunger in a retracted position, operating means for said plunger, an instrumentality for disengaging said operating means from said plunger, a device for resetting said means into engagement with said plunger, a lid holding means carried by said backing member, a hamper guide means, elements engageable with said securing devices, operating means therefor, and connecting means coactively associating the two operating means.

45. In a mechanism for fastening lids on hampers wherein the lids have been previously equipped with staples positioned for engagement with a hamper, a supporting stem, a lid backing member suspended therefrom, a slide member carried by the stem, stapling members hinged to said lid backing member, links connecting the

stapling members to said slide member to cause simultaneous operation thereof, and operating means for said slide member.

5. In a mechanism for fastening lids on hampers wherein the lids have been previously equipped with staples positioned for engagement with a hamper, a supporting stem, a lid backing member suspended therefrom, a slide member carried by the stem, stapling members hinged to said lid backing member, links connecting the 10 stapling members to said slide member to cause simultaneous operation thereof, operating means for said slide member, a lid holding means associated with the lid backing member to retain a lid and its staples in position for engagement by said stapling members, and a hamper guide means for directing a hamper into juxtaposition with the lid.

10. In a mechanism for fastening lids on hampers wherein the lids have been previously 20 equipped with staples positioned for engagement with a hamper, a supporting stem, a lid backing member suspended therefrom, a slide member carried by the stem, stapling members hinged to said lid backing member, links connecting the 25 stapling members to said slide member to cause simultaneous operation thereof, operating means for said slide member, a plurality of lid holding fingers arranged around the periphery of said lid backing member to retain a lid and its staples 30 in position for engagement by said stapling members, and a hamper guide means for directing a hamper into juxtaposition with the lid, said fingers positioned to enter said hamper and reinforce the same to withstand the action of said 35 stapling members.

11. In a mechanism for fastening lids on hampers wherein the lids have been previously equipped with staples positioned for engagement with a hamper, a supporting stem, a lid backing member suspended therefrom, a slide member carried by the stem, stapling members hinged to said lid backing member, links connecting the stapling members to said slide member to cause simultaneous operation thereof, operating means 40 for said slide member, a plurality of lid holding fingers arranged around the periphery of said lid backing member to retain a lid and its staples in position for engagement by said stapling members, a hamper guide means for directing a hamper into juxtaposition with the lid, said fingers positioned to enter said hamper and reinforce the same to withstand the action of said 45 stapling members, an ejecting plunger including a head centered in said backing member and a shaft guided by said stem, yieldable means normally holding said plunger in a retracted position, operating means for said plunger, an instrumentality for disengaging said operating means from said plunger, a device for resetting said means into 50 engagement with said plunger, and connecting means coactively associating the two operating means whereby the ejecting plunger is actuated 55 upon completion of the stapling operation.
